UNITED STATES PATENT OFFICE.

ARTHUR EDWARD ARCHER, OF FULWITH GRANGE, NEAR HARROGATE, ENGLAND.

FORMING AND PRICKING SAND MOLDS FOR CASTINGS.

1,300,103.

Specification of Letters Patent.

Patented Apr. 8, 1919.

Application filed December 27, 1917. Serial No. 209,039.

To all whom it may concern:

Be it known that I, ARTHUR EDWARD ARCHER, a subject of the King of Great Britain, whose post-office address is Fulwith 5 Grange, near Harrogate, in the county of York, England, Great Britain, have invented new and useful Improvements in Forming and Pricking Sand Molds for Castings.

This invention relates to improvements in the method of and in means for the formation and pricking of sand molds or cakes for the production of metal castings carrying a slender part or parts such for instance as points, spikes, shanks, prongs or lugs projecting therefrom, the pricking being for the purpose of forming perforations in the molds or cakes into which the molten metal flows to produce the points or the like of the castings; and the objects of the said invention are, (a) to insure the pricking being accurately effected, (b) to dispense with the practice hitherto existing of forcing the prickers into the sand after it has been rammed into a compact and more or less rigid mass (*i. e.* after the mold has been formed) which has the prejudicial effect of bringing the sand into a condition of increased density at precisely those positions (*i. e.* around the perforations formed by the prickers) where it is an advantage that it should be softer in order to permit the steam and gas attendant upon the inflow of the molten metal to escape, (c) to enable the mold to be formed simultaneously with the pricking thereto, thus saving time and labor due to one operation instead of two as heretofore arising out of separately forming the mold and separately pricking it and (d) to reduce the friction set up by the passage of the prickers into the hard sand which causes their rapid deterioration and renders frequent replacement necessary.

For the purpose of my invention I employ and combine with my means so much of the device known in the art as a spring pricker as consists of a series of prickers secured in a plate which has had such movement relatively to another plate (to which it is attached) as to cause the prickers to be projected through perforations in the latter

plate and in which the free ends of the prickers normally rest which said latter plate has been mainly composed of a replica or replicas of the pattern or patterns (from which pattern or patterns the mold or cake had already been formed) for the purpose of registering the replica or replicas with the mold of such pattern or patterns in the operation of pricking such mold.

I attain the objects above referred to by the mechanism illustrated in the accompanying drawings in which:

Figure 1 is side elevation of the entire apparatus.

Fig. 2 is end elevation of same.

Fig. 3 is top plan view.

Fig. 4 is plan view of base plate herein-after referred to viewed from the underside thereof.

Fig. 5 is side elevation of prickers, with pattern plate hereinafter referred to drawn to a larger scale and,

Fig. 6 is side elevation of the apparatus with pattern plate depressed as hereinafter referred to.

Fig. 7 is a detail view showing in side elevation a part of the pattern plate, and Fig. 8 is a view showing the underside of the same part.

Fig. 9 is a detail view showing in side elevation one of the sliding rods.

The same reference numerals denote the same parts throughout the figures.

1 is a base plate upon which are mounted 85 prickers 3. 2 is a plate (hereinafter referred to as the pattern plate) which carries the actual pattern or patterns 16' (or portions thereof) of the article or articles to be cast. The patterns are preferably formed integrally with the pattern plate 2 and are so arranged in the pattern plate that there shall be a plain margin surrounding the pattern or aggregation of patterns to accommodate the half section of a molding box 5 of any ordinary type and which may be held in position on the pattern plate 2 by any suitable means. The base 1 is bored at suitable positions thereof—in the example illustrated in the drawings—adjacent to the four corners 100 as at 6 to slidely receive rods such as 7, 8, 9,

9" which rods are rigidly secured to the pattern plate 2 as indicated at 10, 11, 12. The borings 6 in the base 1 are preferably somewhat larger in diameter than the diameter of the rods so that the said rods have a latitude of transverse movement in the said borings. A preferred method of securing the rods to the pattern plate consists in such rods being each formed with the flange part 13 which flange parts fit into recesses 14 in the underside of the pattern plate 2, the said pattern plate being bored through and the rods drilled and screw threaded to receive the screw studs 15. It is to be understood that the pattern plate 2 has a reciprocating movement relatively to the base 1. Interposed between the base 1 and the pattern plate 2 and positioned on each of the sliding rods are coil springs 16 or other suitable springs to flexibly hold the pattern plate 2 normally away from the base 1 and to return the pattern plate 2 to normal position after the pattern plate has been depressed as will hereafter appear. The sliding rods and the pattern plate 2 are held in the base 1 by means of the nuts 7', 8', 9' and 9", one of the said nuts in each case serving to adjust the pattern plate 2 into correct position relatively to the pricklers 3 and at the same time to bring the springs 16 into a condition of compression.

In Fig. 3 is shown the outer face of the pattern plate 2 bearing examples of the patterns 16'. 17 are perforations formed in the pattern plate 2 in such positions that they are embraced by the actual patterns. As shown by Fig. 1 the free ends of the pricklers 3 are normally housed in the perforations in the pattern plate 2 and which plate slides on the pricklers whose ends normally are flush or approximately flush with the outer face of the pattern plate 2, but which ends when the pattern plate 2 is depressed as shown by Fig. 6 project beyond such plate.

Fig. 5 illustrates the hitherto known method of holding together and in position an assemblage of pricklers which method is preferably adopted for the purpose of my invention, 18 being a plate preferably of metal and 19 being another plate perforated at desired positions in order to pass the pricklers therethrough, while the heads of the pricklers are interposed between the plates. As clearly shown, the plate 18 is secured to the base plate 1 by means of studs 24 and nuts 25. 20 are distance pieces by means of which a space between the two plates is preserved for the accommodation of the heads of the pricklers. The plates 18 and 19 are held together at suitable positions as indicated at 21. 22 are rods (of which there may be four or more) such rods being rigidly secured at one end to the pattern plate 2 the said rods sliding in perfora-

tions formed for the purpose in the plates 18 and 19, the position of the plates 18 and 19 relatively to the pattern plate 2 being adjusted by means of nuts such as 23 which likewise prevent the plates 18 and 19 becoming separated from the pattern plate 2. 70 The rods 22 may in some cases as will herein-after appear be dispensed with but if employed the base 1 is so perforated as to permit the movement of the rods 22 as will be clearly understood. 75

In order that the depth of the pricking of the mold may be regulated or varied to any desired degree I provide means whereby the pattern plate 2 may be depressed to a less or larger extent thus enabling a corresponding lesser or larger extent of projection of the pricklers through the pattern plate 2. 80 Such means may consist of a suitable number of studs 26 arranged in the base 1 at any desired position thereof, such studs 85 screwing into the base. By rotating the studs 26 which may be effected by a tool inserted in the slot 27 the heads or free ends of the studs may be brought closer to or removed farther from the base 1, it being 90 understood that the pattern plate 2 contacts with the studs 26 on being depressed as shown by Fig. 6. When in the desired position the studs 26 are locked by the nuts 28.

It will be obvious that the pattern plate 95 2 and the patterns are so perforated as to meet the requirements of the particular castings to be produced and that the pricklers have to be so arranged as to co-act with or enter such perforations, the arrangement of 100 perforations 17 shown in Fig. 3 being only by way of example.

In those cases where my means are employed for invariably producing molds from the one pattern or sets of the one pattern 105 thus not necessitating the variation of the pattern plate 2 I dispense with the rods 22 inasmuch as when the device is once set up it may remain wholly intact. When, however, the use of a particular plate carrying 110 a given pattern or patterns is not constant or only intermittent the particular pattern plate and the particular pricklers with their securing plates may be removed and variations of such parts to produce different 115 molds substituted, such substituted elements being secured to the base 1 as hereinbefore described. In this way relatively to the same base and parts accessory thereto, the pattern plate and pricklers may be interchangeable. In such cases the rods 22 are preferably employed to hold the pricklers and the pattern plate when detached from the base intact until again required. 120

The operation is as follows:—

The half section of a molding box (of any ordinary description) is placed on the pattern plate 2 and is filled with sand and such

sand is rammed or squeezed by any suitable means, which means may be operated either manually or by power. The pressure set up by the ramming or squeezing causes the pattern plate and with it the molding box and sand to move toward the base and the prickers to be protruded through the pattern plate into the sand. Thus the mold in the operation of being formed is at the same time pricked.

The base above referred to may take the form of a table or bench and in the latter case several pattern plates and sets of prickers and other parts above described accessory to such pattern and base plates may be arranged or mounted as described in reference to a base plate directly on such bench which accordingly would operate as a base common to the several pattern plates and accessory or co-acting parts, and it is to be understood that the table or bench is included in the term "base plate", wherever such term is herein employed.

I lay no claim to the pricking device as above described as being composed of the parts 3, 18, 19, 20, 21, 22, 23, or to the arrangement of such parts as such device is known, but what I do claim is:—

1. The method of forming and pricking sand molds or cakes for the production of metal castings, consisting of the employment of a pattern or patterns in two parts, one part thereof relatively to the other being flexibly supported and such other part stationary, the moving pattern part (with a half molding box and sand thereon—being together during the formation of the mold) continuously moved in one direction against the supporting influence by the action of ramming the sand to form the mold and continuously returned to the normal position by the supporting influence on the reverse movement of the ramming means, and by which movements, in one direction, the stationary pattern parts are caused to project through apertures provided in the flexibly supported part into the sand to form cavities in the said sand mold to receive molten metal for the formation of part of the casting, the mold being withdrawn from the stationary part on the reverse movement of the flexibly supported part.

2. In means for the formation and pricking of sand molds or cakes for the production of metal castings, the combination of a flexibly supported perforated plate, patterns carried by said plate from which the mold is to be formed, and stationary means for pricking the sand molds in said patterns to provide cavities therein to receive molten metal for the formation of part of the casting, said means operating through the perforated plate and co-acting with said plate to form the equivalent of a single pattern.

3. Means for the formation and pricking of sand molds or cakes for the production of metal castings consisting of the combination with a series of prickers of a plate carrying a pattern or patterns from which the mold is to be formed and a base plate, the said pattern plate being adapted to support a molding box, such pattern plate being so mounted in the base plate as to have a reciprocating movement relatively to the base plate and to which base plate the prickers are secured, the said pattern plate being provided with perforations in which the free parts of the prickers are normally contained and through which perforations such free parts of the prickers project beyond the pattern plate on the movement in one direction of the pattern plate and sand during the formation of the mold or cake, such prickers occupying their normal position on the reverse movement of the pattern plate and sand.

4. Means for the formation and pricking of sand molds or cakes for the production of metal castings consisting of the combination with a series of prickers of a plate carrying a pattern or patterns from which the mold is to be formed and a base plate, the said pattern plate being adapted to support a molding box, such pattern plate being so mounted in the base plate as to have a reciprocating movement relatively to the base plate and to which base plate the prickers are secured, the said pattern plate being provided with perforations in which the free parts of the prickers are normally contained and through which perforations such free parts of the prickers project beyond the pattern plate on the movement in one direction of the pattern plate and sand during the formation of the mold or cake, such prickers occupying their normal position on the reverse movement of the pattern plate and sand and means whereby the extent of projection of the prickers through the pattern plate may be regulated.

5. An apparatus for forming sand molds, comprising a stationary base, pricking members fixed to and upstanding from said base, a pattern plate mounted for reciprocating movement above said base and having openings therein to receive the pricking members, and a mold above the pattern plate and movable therewith.

6. An apparatus for forming sand molds, comprising a stationary base, pricking members fixed to and upstanding from said base, a pattern plate mounted for reciprocating movement above said base and having openings therein to receive the pricking members, a mold above the pattern plate and movable therewith, and means for adjusting the movement of the pattern plate toward the base.

7. An apparatus for forming molds comprising a stationary base, pricking members

upstanding from and fixed to the base, a pattern plate above the base formed with openings to receive the pricking members, means for biasing said plate away from said base, and a molding box supported by said plate.

8. An apparatus for forming molds, as embodied in Claim 7, said biasing means comprising bolts fixed to said plate and slidably

in said base, and springs surrounding the bolts and interposed between said plate and base.

ARTHUR EDWARD ARCHER.
